UNITED STATES PATENT OFFICE.

FRED T. CARPENTER, OF TOLEDO, OHIO.

FLUSH CAR-DOOR.

1,094,835.

Specification of Letters Patent. Patented Apr. 28, 1914.

Application filed July 11, 1913. Serial No. 778,567.

To all whom it may concern:

Be it known that I, FRED T. CARPENTER, a citizen of the United States, and a resident of Toledo, in the county of Lucas and State 5 of Ohio, have invented a certain new and useful Flush Car-Door; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates particularly to flush doors for freight cars, but is not restricted to such use, as it may be used in any connection for which it may be adapted or appropriate.

20 The object of my invention is the provision of a simple, strong and durable door of this character, which is flush with the car side or frame work at all times, whether in open or closed position, is practical and 25 safe to use and is a material improvement over doors of the flush type heretofore used.

Further objects and advantages of the invention will be apparent from the following 30 description.

The invention is fully described in the following specification, and while, in its 35 broader aspect, it is capable of embodiment in numerous forms, a preferred embodiment thereof is illustrated in the accompanying drawings; in which,

Figure 1 is a side elevation of a portion of a wood frame freight car embodying the invention with the door in closed position. Fig. 2 is a section on the line $x-x$ in Fig. 1. 40 Fig. 3 is a vertical section on the line $x'-x'$ in Fig. 2. Fig. 4 is a horizontal section of a side portion of a steel frame car embodying the invention with the door in closed position. Fig. 5 is a vertical section thereof 45 on the line $w-w$ in Fig. 5. Fig. 6 is an enlargement of a portion of the section $w-w$. Fig. 7 is an enlargement of a portion of the section $x-x$ in Fig. 1, and Fig. 50 8 is a perspective view of a side portion of a steel frame freight car with my door in closed position.

Referring to the drawings, 1 designates a side of a wooden type of freight car, 1^a the side of a steel frame type of freight car, 55 and 2 the sliding flush door thereof. In the case of a wooden frame type of car the

front and rear jamb-posts are preferably of wood and are designated 3 and 4, respectively, in Figs. 1 and 2, while in the case of a steel frame type of car two of the customary external reinforcing posts or members, which are usually of Z-form are employed as the front and rear jamb-posts, and such posts are designated 3^a and 4^a, respectively, in Figs. 4 and 8. The Z-bar posts have their outer flanges extending toward each other to lap and protect the respective side edges of the door when in abutment with such posts. The jamb-posts have their outer sides substantially flush with the 60 outer car side and the center post 5, which is disposed between the two jamb-posts is spaced inward from the outer side of the car to permit the door to have free sliding movements past the same. The space between the front jamb-post and the center post 5 is open to provide the door opening, while the space between the rear jamb-post and center post is closed preferably by a metallic plate or sheeting 6, which is inwardly spaced from the car side and has its side edges secured in suitable manner to the 65 posts between which it is disposed.

7 designates the upper side beam of a car and 8 the lower side beam thereof, which 70 may be of wood, steel or other material, as desired.

The door is suspended from a track 9 beneath fascia boards 7^a on the side beam 7 by roller-brackets 10, and its lower edge slidingly operates over a sill-strip 11, in vertically spaced relation thereto, as best shown in Fig. 3. The sill-strip 11 extends the entire distance between the jamb-posts 3 and 4, and is mounted on the lower side sill 8 in case of a wooden construction of car, and upon a sill part 8^a projecting from the side beam 8 in a steel frame car. The sill-strip is of angle-bar form in cross-section with its inner flange extending upward. The track 9 is preferably Z-bar form in cross-section with its inner flange extending upward and bolted or otherwise suitably secured to the upper side beam 7, and its outer flange extending downward in position to coact with the upper edge of the door to limit the outward movements thereof relative to the car side and to retain the rollers on the brackets 10 in contact with the track.

110 A Z-bar strip 13 is preferably secured to the lower edge of the door with one flange

extending upward at the outer side of the door and bolted or otherwise suitably secured thereto, and with the other flange extending downward beneath the door in position to have transverse abutting contact with guide-tongues 14, which are carried by the sill-strip 11 at the outer side of the lower flange of the strip 13, as best shown in Figs. 1 and 6. In order that the door may have free sliding movements relative to the guide-tongues 14 and at the same time be held closely against the front jamb-post 3, 3^a, as the case may be, and the center post 5, when the door is in closed position, to prevent a rattling thereof, the opposite end portions of the bottom flange of the door strip 14 are provided with studs or offset portions 15 in position to have camming contact with the inner side of the respective end tongues 14 to coat therewith when the door is closed to force the lower edge of the door against the registering stationary portions of the car. Tongues 16 also project from the jamb-posts 3 and 4 in position to overlap the respective edges of the door when in substantially abutting contact with the respective posts. While it is preferable to make the strip 13 of Z-bar form, a strip of other suitable form for coacting with the guide-tongues 14 may be substituted therefor, if desired.

17 designates a lock-bolt, which is carried by the door at the lower portion thereof and is adapted to have its lower end projected into openings in the sill-strip 11 to retain the door in open, partially open or closed positions. An angle-bar strip 18 is secured to the post 5 with one flange forming a facing for the side of the post which is exposed to the door opening and with the other flange lapping the outer side of the post and spaced therefrom at its edge, as shown in Fig. 2. A similar angle-bar strip 19 is secured to the rear edge of the door with one flange lapping the inner side edge thereof in spaced relation thereto to have interlocking engagement with the spaced edge of the strip 18 when the door is closed, whereby to provide a close joint between the rear edge of the door and post 5 when the door is in closed position, as shown in Fig. 2.

It will be apparent with my improved

construction of door that the same always stands in flush relation to the car side 55 whether the door is in open or closed position, thus making it impossible to tear the door from the car by "side swiping," as is so frequently the case with the forms of flush doors which stand out from the car 60 sides when the doors are in open position. It is also evident that all guiding parts for the door are set either flush with or within a plane which is flush with the side of a car to prevent such parts from being struck 65 and torn from the car by passing trains, or in any other manner.

I wish it understood that my invention is not limited to any specific construction, form or arrangement of the parts except in 70 so far as such limitations are specified in the claim.

Having thus described my invention, what I claim as new, and desire to secure by Letters Patent, is,—

75

In a car, a door casing comprising spaced apart front and rear jamb-posts of Z-bar form with their outer flanges extending toward each other, said posts being substantially flush with the outer side of the car, a 80 center post intermediate said jamb-posts set inwardly from the outer vertical plane of the jamb-posts, top and bottom side beams connecting said posts, a closure wall extending in substantially the plane of the center-post from the center-post to the rear jamb-post, a track carried by the upper side beam with its outer edge substantially flush with the outer sides of the jamb-posts, a door hung from said track flush with the side of 90 the car to close the space between the front and center posts and adapted to slide toward the rear post without said closure wall, a sill-strip extending between the jamb-posts beneath the door, and guide-members rising 95 from said sill-strip within the vertical outer side plane of the jamb-posts and coacting with the lower edge of the door to guide the sliding movements of the door.

In testimony whereof, I have hereunto 100 signed my name to this specification in the presence of two subscribing witnesses.

FRED T. CARPENTER.
